UNITED STATES PATENT OFFICE.

CHARLES F. EDMINSTER, OF WYANET, ILLINOIS.

SCALE.

SPECIFICATION forming part of Letters Patent No. 553,978, dated February 4, 1896.

Application filed April 23, 1895. Serial No. 546,850. (No model.)

To all whom it may concern:

Be it known that I, CHARLES F. EDMINSTER, a citizen of the United States, residing at Wy-
5 anet, in the county of Bureau, State of Illi-
nois, have invented certain new and useful
Improvements in Scales, of which the follow-
ing is a specification, reference being had
thereto to the accompanying drawings.

This invention relates to certain new and
10 useful improvements in scales of that class
known as "platform-scales;" and it has for its
objects, among others, to provide a simple and
cheap scale in which the parts are so con-
structed and arranged as to avoid the neces-
15 sity of providing a pit beneath or an elevation
above the ground.

The levers are suspended from suitable
means and lie alongside and parallel to and
20 between the timbers of the scale-frame and
the floor-joist and are connected by a short
lever and by suitable means to the scale-beam,
the mechanism beneath the platform being
all suspended within the depth of the scale-
25 frame extending neither above nor below this
depth and thus permitting a wagon or stock
scale to be built flat or substantially flat upon
the ground or floor.

The mechanism also is simplified and is
thus rendered more durable and inexpensive
30 and less liable to injury or derangement.

Other objects and advantages of the invention
will hereinafter appear and the novel
features thereof will be particularly pointed
out in the appended claims.

35 The invention is clearly illustrated in the
accompanying drawings, which, with the letters
of reference marked thereon, form a part
of this specification, and in which—

Figure 1 is a top plan with the flooring in-
40 dicated by dotted lines. Fig. 2 is a vertical
longitudinal section on the line 2 of Fig. 1,
looking in the direction of the arrows.

Like letters of reference indicate like parts
in both of the views.

45 Referring now to the details of the draw-
ings by letter, A designates the frame of any
suitable or well-known construction, consist-
ing of longitudinal and transverse timbers,
as shown, and at one side formed with the
50 passage-way A' for the rod and short lever
which connects the transverse connecting-rod
with the weigh-beam, the latter not being

shown. At each corner is provided a cap-
piece B and suitably secured to the longitudi-
55 nal and transverse timbers of the scale frame,
as shown, and these cap-pieces are provided
with common or ordinary clevis bearings or
hangers B', from which are suspended in the
ordinary manner the four main levers C, as
60 shown in both views, these levers having upon
their under sides the additional bearings, as
shown at b, of any well-known or suitable
form of construction. These levers C extend
65 in pairs at opposite sides of the scale,
and at their inner or adjacent ends are at-
tached by means of the common double clevis
or point bearings D to the short lever E, which
are attached to the transverse connecting-rod
70 F, which rests upon knife-bearings at G G,
and one end of this transverse connecting-rod
F is extended in the passage-way A', as shown
in Fig. 1, and attached thereto is a short le-
ver or arm H, which is designed to transmit
75 the pressure therefrom to a common rod I de-
signed to extend upward and to be connected
with the weigh-beam. (Not shown.) This
rod is adjustable in a slot h of the arm H, as
seen in Fig. 1.

Suitable stay-links I' are provided, one in
80 each corner, as seen in Fig. 1, which connect
the floor-joist J to the end timbers of the scale-
frame, said floor-joist J being provided with
openings j, as seen in Fig. 1, for the passage
85 of the rod F, and said joists are supported at
their ends upon the transverse plates K, which
at their ends support the casting hooks or
bearings b. The flooring L (indicated by dot-
ted lines in Figs. 1 and 2) is supported upon
these floor-joists in the usual manner.

In practice the pressure or weight is trans-
90 mitted from the levers C C to the short levers
E E and through the rod F to the weigh-beam.
The parts constituting the scale are compactly
arranged, requiring no pit beneath or eleva-
95 tion above the ground and are all arranged
within the depth of the timbers of the scale-
frame.

Modifications in detail may be resorted to
without departing from the spirit of the in-
vention or sacrificing any of its advantages.
100 The lever H may be extended either way from
the rod F, as shown. In one position the
pressure is communicated directly to the
weigh-beam and in the other is connected by

means of a common scale-evener, by means of which the beam-box may be placed in any desired direction or distance from the scale proper.

5 What I claim as new is—

1. The combination with the scale-frame and the caps at the corners, of the levers suspended at their outer ends from said caps and extended parallel with the longitudinal timbers of the frame and within the height thereof, substantially as described.

2. The combination with the scale-frame and the caps at the corners, of the levers suspended from said caps parallel with and along-
15 side of the timbers of said frame and within the height thereof and the short levers connected by clevis to the adjacent ends of the first-mentioned levers in the same vertical plane, substantially as described.

20 3. The combination with the scale-frame and the caps at the corners, of the levers suspended from said caps and extended toward

the center, the transverse rod connected with the weigh-beam and the short levers connected with said rod and with the adjacent ends 25 of the levers in the same vertical plane therewith, substantially as described.

4. The combination with the scale-frame and the levers suspended from the corners thereof within the height of the frame parallel with the side timbers thereof, of the floor-joists within the height of the frame, the transverse rod connected with said levers in the same vertical plane therewith and with the weigh-beam, and the stay-links connecting the floor-joists with the end timbers of the scale-frame, substantially as described.

In testimony whereof I affix my signature in presence of two witnesses.

CHARLES F. EDMINSTER.
